UNITED STATES PATENT OFFICE

2,469,194

REACTANCE TUBE CIRCUIT

Jean L. Delvaux, Paris, France, assignor to General Electric Company, a corporation of New York

Application July 16, 1947, Serial No. 761,326
In France December 12, 1942

Section 1, Public Law 690, August 8, 1946
Patent expires December 12, 1962

5 Claims. (Cl. 332—28)

1

This invention relates to improved reactance tube circuits and particularly to reactance tube circuits for modulating the phase or frequency of electrical oscillations.

An object of the invention is to provide an improved, simple and inexpensive reactance tube circuit which will operate to modulate in phase or frequency the oscillations in an associated oscillator tank circuit.

Another object of the invention is to provide a reactance tube circuit which will operate effectively over a wide range of frequencies; and a further object is to provide a reactance tube circuit so arranged that departures of the reactance tube current from a quadrature relationship with the voltage of an associated oscillator are minimized.

An additional object of the invention is to provide a reactance tube circuit particularly adapted for use with an oscillator of the three terminal type, wherein two alternating voltages of opposite phase are produced between two extreme or opposite terminals, respectively, and a third common or nodal terminal or point.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Fig. 1 is a diagram of a reactance tube circuit in association with an oscillator and Fig. 2 is a diagram showing a modification of the reactance tube circuit.

With reference to Fig. 1 of the drawings, an oscillator is shown comprising an electron discharge device 1 connected with a tapped inductance 2 and capacitor 3 in a Hartley oscillator circuit, control electrode connection to the tank circuit, formed by inductance 2 and capacitor 3, being through a capacitor 4, and the cathode connection being through capacitor 5. Anode operating potential is supplied from a suitable source such as the B+ terminal of a battery as shown.

Across the end terminals 7 and 8 of the oscillator tank circuit appears as alternating voltage of which the nodal point is represented by the tap terminal 9 of the inductance, this tap being grounded for alternating currents through capacitor 5. It will be apparent that the terminal 9, as far as alternating voltages are concerned, is the same as the ground connection shown in the drawings. Each of terminals 7 and 8, ac-

cordingly, carries an alternating voltage with respect to the grounded intermediate point or terminal 9, and these two voltages are of opposite phase, though not necessarily of equal magnitudes.

Connected to terminals 7 and 8 is a reactance tube circuit comprising an electron discharge device 10 with its cathode connected to the nodal point, as represented by tap 9 or by ground, and with its anode connected to terminal 7. The control electrode 11 is directly connected to an intermediate point represented by the interconnection of resistors 12 and 13 in a voltage dividing network. This network includes low impedance direct current blocking capacitors 14 and 15 and is arranged to furnish to control electrode 11 a fractional portion of the alternating voltage existing on terminal 8. Added to this fractional voltage by a capacitor 16 is a phase shifted voltage derived from terminal 7. The voltage applied by capacitor 16 to the control electrode is nearly in quadrature with the voltage at terminal 7, and added to this phase shifted voltage is a voltage from the voltage divider network 12, 13 which is 180 degrees out of phase with the anode voltage from terminal 7. These two voltages provide a compensated or corrected control electrode voltage such that the reactance tube anode current is maintained with a minimum departure from quadrature with respect to the oscillator voltages.

The anode current, i_p , of an electron discharge device, such as triode tube 10, is related to the alternating component of the anode voltage, e_p , the alternating control electrode voltage, e_g , and the anode resistance of the device, r_p , if the amplification factor of the tube is μ , in accordance with the equation:

$$i_p = \frac{e_p + \mu e_g}{r_p}$$

The voltage applied to the control electrode 11 through the voltage dividing network 12, 13 is in phase opposition to e_p and may be proportioned, by adjustment of the value of resistor 12, or otherwise, to be such that $\mu e_g = (-) e_p$. The in-phase anode current of the tube due to the alternating anode voltage component would be thus overcome by the provision of this voltage from terminal 8 through the voltage divider.

In addition, however, it will be found that the control electrode voltage supplied from terminal 7 through the phase shifting network 16, 13 is not exactly in quadrature with the voltage on terminal 7 but contains a small component in

3

phase with the voltage of terminal 7. This component, also, may be overcome by increasing the voltage from terminal 8 to a value slightly greater than just enough to fulfill the requirements of: $\mu e_p = (-) e_p$. The final adjustment should be, accordingly, such as to make

$$e_t = (-) \frac{e_p}{\mu} + e_t'$$

where e_t' is the in-phase component of the voltage developed in the phase shifting network across resistor 13 by current from terminal 7 through capacitor 16.

Some small further corrections may be necessary to compensate for inherent circuit capacitances, including interelectrode capacitances of device 10. The inherent capacitance existing across resistor 12 is represented in Fig. 1 by the condenser 17 shown in dotted lines.

It may be found convenient to provide a variable capacitor as capacitor 16, as well as a variable resistor as resistor 12, as they are both shown in Fig. 1, to permit any necessary adjustments to be made. Other suitable elements may, of course, be made adjustable instead of, or in addition to those mentioned, if desired, or the proper values of fixed elements may be utilized throughout.

A terminal 18 is shown connected to that end of resistor 13 which is connected to capacitor 15. A suitable biasing potential may be applied in any known manner to this terminal, and a modulating voltage, as for instance an audio voltage, may also be applied to alter the conductance of the tube 10 in a known manner. Capacitor 15 should be of low impedance at the frequency of the oscillator, but of high impedance at the frequency of modulating voltages applied to terminal 18.

In operation it will be found that the anode current of reactance tube 10 will not depart by more than a small angle from a quadrature relationship with the voltage of terminal 7 over a relatively wide range of frequencies generated by oscillator tube 1.

It will be apparent to those skilled in the art that the voltages applied to the phase shifting network or to the voltage dividing network may be taken from other taps along inductance 2, or from a voltage dividing capacitance network replacing capacitor 3, as may be best suited to a particular situation, and other similar alternatives or modifications will be apparent to those skilled in the art.

In the modification of Fig. 2, is shown a tickler feedback, tuned grid type oscillator comprising discharge device 4, grid tank inductance 2 and capacitor 3, and inductance 19 inductively coupled to inductance 2. The operating principles of such oscillators are well known. Grid coupling capacitor 4 and grid leak resistor 6 perform well known functions, and capacitor 5 serves to ground for alternating current voltages the juncture 20 of windings 2 and 19. These two windings may be, if desired, separated by a capacitor or the like for direct current voltages, but interconnected for alternating currents. Positive operating potential is provided by a suitable source, such as the battery shown connected to supply B+ potential to the anode circuits of the discharge devices employed.

The oscillator of Fig. 2 provides voltages on terminals 21 and 22 with respect to juncture 20, grounded for alternating voltages, which are of opposite phase. The voltage on terminal 22 is applied to a voltage divider network comprising

capacitors 23 and 24 connected in series to ground or, to any desired point at the alternating voltage node. The control electrode 11 of electron discharge device 10 receives from its connection with the juncture of these two capacitors a fraction of the voltage of terminal 22 without substantial phase shift.

A voltage component is derived from the voltage on terminal 21 shifted in phase by nearly 90 degrees which appears at the juncture between a resistor 25, which is preferably variable as shown, and capacitor 24 connected in series from terminal 21 to ground to form a phase shifting network. A low impedance direct current blocking capacitor 26 is included to complete the circuit from terminal 21 to ground while preventing the B+ potential from reaching control electrode 11.

The two voltage components, from the voltage divider comprising capacitors 23 and 24, and from the phase shifting network comprising resistor 25 and capacitor 24, are algebraically added to energize control electrode 11. The proportionment of these two voltages is in accordance with the principles discussed in connection with Fig. 1. That is, the voltage provided from terminal 21 is shifted in phase by nearly 90 degrees at the point of connection of the control electrode 11 to the phase shift network 25, 24. The correcting voltage derived from voltage divider network 23, 24 is of sufficient magnitude and correct phase to overcome the anode current variations caused by the alternating component of anode voltage and to correct for the slight displacement from quadrature of the phase shifted voltage from terminal 21 which is applied to the control electrode. In operation, as discussed above in connection with Fig. 1, the circuit of Fig. 2 provides an anode current in reactance tube 10 differing from a quadrature relationship with the oscillator voltage, at terminal 21, by not more than a small angle throughout a relatively wide frequency band. The relationship may be made to be exactly quadrature at one frequency, and it will then be very nearly exactly quadrature for a substantial deviation from this frequency.

For the circuit of either Fig. 1 or 2, it will be obvious that in-phase power may be provided, if desired, by reactance tube 10 if the voltage derived from the voltage divider network is made larger than necessary to provide the compensating functions described above, or that in-phase power will be absorbed by the tube if the compensating voltage is reduced below the value necessary for full compensation. The quadrature component, of course, may be thought of as being a current drawn from or supplied to the oscillator. Since it is in quadrature, it represents no power transfer between the oscillator and the reactance tube circuit.

It may be found convenient to furnish variable elements to perform the functions of resistor 25 and capacitor 23, respectively, both as shown in Fig. 2, or to provide such other adjustable elements as are desired to furnish the flexibility for adjusting the circuit for different conditions. Elements of fixed values, however, are desirable if cost is important and if operation is to be within relatively narrow frequency limits.

Terminal 18 is provided as a point for connecting through a suitable resistor 27 a biasing potential and, if desired, a modulating voltage, as heretofore explained in connection with Fig. 1.

While I have shown only certain preferred embodiments of my invention by way of illustration, many modifications will occur to those

skilled in the art and I therefore wish to have it understood that I intend, in the appended claims, to cover all such modifications as fall within the true spirit and scope of my invention.

What I claim as new and desire to secure by Letters Patent of the United States is:

1. A reactance tube modulator comprising means for generating two voltages of opposed phase with a common predetermined nodal point, an electron discharge device with an anode, a cathode connected for alternating voltages to said point, and a control electrode, means for applying one of said voltages to said anode, means for applying a voltage substantially in quadrature with said one voltage to said control electrode, means for deriving from the other of said two voltages a correcting voltage and for applying said correcting voltage to said control electrode whereby conduction of in-phase anode current by said discharge device is minimized, and means for applying a modulating voltage to control the intensity of current conducted by said device.

2. A reactance tube circuit, adapted for use with a generator providing two alternating voltages of opposite phase with respect to a predetermined nodal point on two respectively opposite terminals, said circuit comprising an electron discharge device with an anode connected for alternating current to one of said terminals, a control electrode, and a cathode connected for alternating current to said nodal point, a phase shift network for providing a control voltage to said control electrode which is nearly in quadrature with the voltage of said one terminal, and a voltage dividing network for applying a voltage derived from and in phase with the voltage of said other terminal to compensate for the deviation from quadrature of said control voltage and to compensate for the in-phase conduction of said device in response to the alternating voltage of said one terminal.

3. A frequency modulated wave generator comprising an oscillator and a reactance tube; said reactance tube having a control electrode connected to receive a voltage nearly in quadrature with a first voltage developed in said oscillator, an anode connected to conduct a reactive current which traverses a frequency controlling element of said oscillator, and a cathode; said generator being characterized by means associated with said

oscillator for developing a second voltage in phase opposition to said first voltage, and means for applying a predetermined fraction of said second voltage to said control electrode to minimize the in-phase component of said current.

4. A reactance tube circuit, for cooperation with an oscillator arranged to generate two alternating current voltages with respect to a predetermined reference point which are of the same frequency but of opposite phase at two oscillator terminals, said circuit including an electron discharge device with an anode, a cathode and a control electrode, a phase shift network comprising a reactance element and a resistance element for providing to said control electrode a voltage component approximately in quadrature with said two voltages, and a voltage divider network arranged to furnish a predetermined fraction of one of said voltages without phase shift to said control electrode whereby components of anode current in said device in phase with either of said two oscillator voltages are minimized.

5. In a frequency modulated wave generator comprising an oscillator for providing an alternating voltage between each of two respective terminals and an intermediate terminal, said voltages being in phase opposition at said two terminals; a reactance tube with an anode arranged to conduct reactive current from said oscillator, a control electrode connected to a phase shifting network arranged to supply thereto from a predetermined one of said two terminals a voltage nearly in quadrature with said alternating voltages, and a cathode connected to said intermediate terminal; a phase correcting network for said reactance tube comprising means for applying a voltage derived without phase shift from the voltage on the other of said two terminals to minimize the effect of departure from quadrature of said control electrode voltage.
